QUICK ACTION PRECISION VISE

Harold G. Renner, Detroit, Mich.

Application August 1, 1947, Serial No. 765,529

1 Claim. (Cl. 81—26)

1

This invention relates to vises and particularly vises designed to maintain accurate parallelism of the clamping faces of their jaws.

An object of the invention is to improve a vise of the type in which a jaw slides on a base to and from a fixed jaw, and is clamped to the base in selective positions by setting up a tensional reaction between the sliding jaw and an anchorage member slidably confined in the base, the improvement consisting in a provision for interlocking the anchorage member and base by means of serrations.

Another object is to form said serrations in a novel and relatively inexpensive manner.

Another object lies in attaching to said anchorage member a shank extending upwardly through the sliding jaw to set up said tensional reaction, imposing such reaction on a face of the sliding jaw inclined to the direction of sliding to cam said jaw forwardly responsive to said reaction, affording said shank a forward and back play in the sliding jaw to permit the desired camming effect, and yieldably urging the shank to its forward limit of such play.

Another object is to dispose an anchorage member for the sliding jaw of a vise in a chamber in the vise base, elongated in the direction of travel of said jaw, and to form mating screw threads in said chamber and on the anchorage member, and to afford the anchorage member an up and down play adequate for interlocking or releasing said threads.

These and various other objects are attained by the construction hereinafter described and illustrated in the accompanying drawing, wherein:

Fig. 1 is a top plan view of my improved vise.
Fig. 2 is a side elevational view thereof.

Fig. 3 is a longitudinal vertical sectional view taken on the line 3—3 of Fig. 1.

Fig. 4 is a cross sectional view, taken on the line 4—4 of Fig. 3.

In these views, the reference character 1 designates an elongated substantially rectangular base, fixedly carrying on one of its ends a jaw 2, formed integral with the base in the illustrated embodiment of the invention. Slidable on the base to and from the jaw 2 is a jaw 3 having a pair of guide flanges 4 downwardly projecting from the lateral margins of its bottom face and fitting in guideways 5 marginally formed in the base. The jaws 2 and 3 have parallel work-clamping faces 6 accurately perpendicular to the top face of the base. The sliding jaw has a cam face 7 extending downwardly and rearwardly

2

from the top of said jaw, preferably at an angle of forty-five degrees to the direction of sliding travel. Said jaw also has a rearward extension 8 at the bottom of said cam face, such extension having a relatively slight vertical thickness.

Extending lengthwise of the base, from end to end thereof, is a chamber 9, preferably a drilled hole tapped with a fairly fine standard V-type screw thread, as for example, thirty-two threads to the inch. A slot 10 opens from the chamber 9 to the top face of the base, such slot extending from the jaw 1 to the rear end of the base and having a width considerably less than the diameter of said chamber. Disposed in the chamber 9 is an anchorage member 11 for the sliding jaw, preferably somewhat elongated lengthwise of said chamber, the top surface of said anchorage member being transversely arcuate, conforming to the wall of said chamber and being formed with a partial male screw thread, such as to accurately mate with the female thread formed by the wall of said chamber. The described anchorage member may be simply formed by grinding away its sides and bottom after initially cutting a full thread adapting said member to screw into the chamber 9, such grinding affording said member a vertical play in the chamber 9, such that the remaining serrations of said member may be engaged with or disengaged from the interior serrations of the chamber 9. The anchorage member is attached to the lower end of an elongated shank 12 which extends upwardly through the slot 10 and through a slot 13 vertically bisecting the rear portion of the sliding jaw. It is preferred to insert the shank 12 in a slot formed in the front end portion of the member 11 and to pivotally connect said member to the shank, as by a pin 14. The shank 12 extends transversely to the cam face 7, and the forward end of the slot 13 has a similar relation to said face. In passing through the slot 13 the shank has flat lateral faces to engage the opposed walls of such slot, and an end portion 12a of the shank projecting above the cam face 7 is cylindrical and threaded to receive a nut 15. By tightening such nut against the face 7, the anchorage member may be drawn into interlocking engagement with the top face of the chamber 9 and a forward thrust may then be applied to the sliding jaw. A spring 16 formed by an elongated strip of sheet metal projects from the extension 8 of the sliding jaw forwardly into the slot 13 and has its forward end downwardly curved to apply a forward thrust to the shank 12. Said spring has an integral enlargement

16a at its rear end secured by screws 17 to the extension 8.

In use of the described vise, an object to be clamped is placed against the jaw 2 and the jaw 3 is slid forward to engage said object, the anchorage member being then in a lowered position in the chamber 9, so that it may travel freely with the jaw 3. The operator now screws the nut 15 down on the threaded end of the shank, drawing the latter up together with the member 11 and thus interlocking the threads of such member with those of the chamber 9. As the nut 15 applies further pressure to the face 7, the jaw 3 is cammed forward to tightly clamp the object against the jaw 2. The forward edge of the slot 13 is moved slightly away from the shank 12 during this clamping travel of the jaw 3, the spring 16 yielding to permit such movement. As soon as the nut is retracted from the surface 7, the spring 16 slides the jaw 3 slightly away from the clamped object, allowing a ready removal of such object. The anchorage member continues, however, to retain the jaw 3 in place to be again cammed to the same clamping position, in case another object of the same size is inserted between the jaws. Thus the described vise lends itself to quantity production work in which a plurality of like work pieces are required to be held in sequence in the vise. If it is necessary to retract the sliding jaw in excess of its camming travel, the anchorage member is releasable by applying a slight downward pressure to the shank 12.

Forming screw threads on the top faces of the member 11 and chamber 9 to afford interlocking of said faces is a rapid and inexpensive method of serrating said faces and assuring a desired uniform spacing of the serrations. It is to be noted that it would be a relatively difficult matter to serrate in any other manner the top face of such a chamber as is indicated at 9. It would further be difficult to produce in any other manner, than has been described, serrations in the top face of the anchorage member suited to fully mesh with the threaded wall of the chamber 9, while readily releasable from such wall.

While the described vise may be inexpensively produced, it avoids the slight upward tilting of the work-engaging end of the sliding jaw that primarily detracts from the accuracy of most inexpensive vises. It is evident that such tilting may not occur in the described vise, since the shank 12 is extended in close proximity to the lower edge of the clamping face of the sliding jaw.

It is a further advantage of the described vise that the means provided for imposing a clamping pressure on the sliding jaw does not materially tend to bow the vise base upwardly between its ends as do many vises in present day use. While such distortion of the base is of small magnitude, it is sufficient to seriously detract from accuracy.

What I claim is:

A vise comprising a base, a pair of clamping jaws on the base, one slideable toward the other, an anchorage member for the sliding jaw, the base having a chamber beneath the sliding jaw elongated in the direction of sliding of said jaw and receiving the anchorage member, the base also having a slot opening from said chamber to the top face of the base and extending lengthwise of said chamber, the width of said slot being less than that of the anchorage member, serrations extending in a substantially transverse relation to said chamber in the top faces of the chamber and anchorage member and proportioned to intermesh, a shank attached to the anchorage member and extending upward at a rearward inclination through said slot and through the sliding jaw, such jaw having a slot receiving the shank and extending to the rear end of such jaw and affording the shank a forward and back play, such slot having a wall adjacent to and forward of the shank and conforming to the shank inclination, a spring having an end thereby mounted on the rear end of the sliding jaw and projecting forwardly in said slot of the sliding jaw to engage said shank, and means reacting between the shank and sliding jaw to stress the anchorage member upwardly and interlock its serrations with those of said chamber.

HAROLD G. RENNER.
